METHOD OF MAKING SHOES

Samuel Bown, St. Louis County, Mo., assignor to
 International Shoe Company, St. Louis, Mo., a
 corporation of Delaware

Application November 11, 1933, Serial No. 697,572

13 Claims. (Cl. 12—146)

This invention relates to a method of making shoes, and has special reference to a method of making a vamp structure preparatory for embodiment in shoes.

5 In a specific sense the present invention comprises a method of making a vamp structure including inner and outer members simultaneously perforated while parts thereof are secured together by permanent attaching means, in combination with a box toe member secured between the toe portions of said inner and outer members in a relationship in which preformed openings in the box toe member register with the previously formed openings in said inner and 10 outer members.

15 Objects of the invention are to provide an improved method of making a vamp structure comprising superimposed inner and outer members of flexible and pliable material attached together in superimposed relationship and simultaneously perforated throughout selected areas thereof to provide openings which may function both as ventilating and as ornamenting means; to provide a box toe member with openings there- 20 through adapted to be brought into registration with the openings through said inner and outer members when the box toe member is assembled in proper position between said inner and outer members; to provide a novel method of locating the 25 box toe member in proper position upon the inner member and the outer member upon the box toe member in a position in which the openings through said three members are in registration; and to attach said three members together 30 in their final relationship.

35 Another object of the invention is to provide an improved method for assembling together the three members of a vamp structure consisting of inner and outer members and an interposed box toe member having preformed perforations registering with perforations through said inner and outer members formed before the placement of the box toe member in connection with said inner and outer members.

40 Another object of the invention is to provide an improved method of making a vamp structure comprising flexible and pliable inner and outer members having portions thereof permanently attached together and provided with perforations formed through said two members while 45 they are attached together, in combination with a box toe member having preformed perforations therethrough located between the toe portions of said inner and outer members and attached 50 thereto in a relationship in which the perfora-

tions through said box toe member register with the perforations through said inner and outer members.

5 Other objects of the invention should be apparent from the following description, reference being made to the annexed drawings, in which—

Fig. 1 is a plan view of the outer member of the vamp structure, a part thereof being broken away to disclose the underlying inner member.

Fig. 2 is a longitudinal sectional view on the 10 line 2—2 of Fig. 1.

Fig. 3 is a plan view similar to Fig. 1 showing the perforations formed through the inner and outer members after they have been assembled in the relationship shown in Figs. 1 and 2. 15

Fig. 4 is a side edge elevation of the attached inner and outer members of the vamp structure shown in Fig. 3.

Fig. 5 is a longitudinal sectional view on the line 5—5 of Fig. 3. 20

Fig. 6 is a plan view of the box toe member having the perforations therethrough adapted to register with the perforations through the inner and outer members of the vamp structure.

Fig. 7 is a longitudinal sectional view of the 25 box toe member on the line 7—7 of Fig. 6.

Fig. 8 is a plan view of the box toe member with portions of the outer member broken away, and showing the manner in which the box toe member is assembled and located in proper position between the inner and outer members, so that the preformed perforations through the box toe member register with the perforations that are formed through the inner and outer members before the box toe member is located and 30 placed between said inner and outer members. 35

Fig. 9 is a longitudinal sectional view of the 40 vamp structure on the line 9—9 of Fig. 8, the template being shown in side elevation.

Fig. 10 is a perspective view of the template 45 employed to locate the box toe member in proper relationship with respect to the inner and outer members of the vamp structure, so that the preformed perforations through the box toe member will register with the preformed perforations through the inner and outer members.

My improved vamp structure comprises a flexible and pliable outer member 1, a correspondingly shaped flexible and pliable inner member 2 and a box toe member 3, said three members 50 being processed and assembled in proper cooperative relationship substantially as herein shown and described.

The members 1 and 2 are of approximately the same size and shape. After said members 1 and 55

2 are formed and before they are perforated a relatively thick and heavy coat of cold quick drying cement 4 is placed upon the rear portion of that surface of the member 2 that is toward the member 1 or upon the corresponding surface of the member 1 or upon said surfaces of both of said members 1 and 2, said heavy coating extending about to the line 5 and covering the entire surface of at least one of said members. A lighter coating 6 of similar cement is applied to the remaining surface of the member 2 or to the member 1 or to both of said members 1 and 2.

Then the member 1 is superimposed upon the member 2 while both of said members are spread flatwise, the edges of said two members being in approximate registration and arranged symmetrically, and pressure is applied to cause the cement coatings 4 and 6 to form an adhesive attachment securing said two members together.

20 Next, and after the adhesive cement has dried to a sufficient extent to hold the members 1 and 2 in proper relationship, numerous perforations 7 are died or cut through both of said members in front of the line 5 and numerous perforations 8 are died or cut through both of said members to the rear of the line 5. All of these perforations may be died or cut simultaneously.

Also numerous perforations 9, corresponding in number and in spacing to the number and spacing of the perforations 7, are died or cut through the box toe member 3 and said box toe member is provided with attenuated or tapering edges 10 formed by skiving said member 3 along its edges. The perforations 9 are of somewhat larger diameter than the perforations 7, which construction facilitates the placement of the toe box member 3 between the members 1 and 2 in such a relationship that the perforations 9 register with the perforations 7 through both of said members 1 and 2.

45 The template which I employ to locate the member 3 in proper relationship for attachment to the members 1 and 2 comprises a body 11 having a plurality of upwardly extending parallel pins 12.

After the members 1 and 2 have been attached permanently by the cement 4 and temporarily by the cement 6, the toe portions of said members 1 and 2 are detached or pulled apart from the front rearwardly approximately to the line 5, and the member 2 is placed upon the template 11 with the pins 12 projecting through a corresponding number of the holes 7 through said member 2, the toe portion of the member 1 being rolled or supported upwardly out of engagement with the pins 12.

The box toe member 3 is then coated with cement and placed upon the upper surface of the member 2 in proper relationship thereto, the pins 12 being extended through a corresponding number of the holes 9 and thereby bringing all of said holes 9 into registration with a corresponding number of the holes 7 through the inner member 2 of the vamp structure.

65 Then the toe portion of the member 1 is pressed downwardly upon the cement coated upper surface of the member 3 and sufficient pressure is applied to cause said cement to form a strong connection uniting the members 1 and 2 to the 70 interposed member 3 in a relationship in which the holes 9 through the member 3 register with a corresponding number of holes 7 through both of the members 1 and 2. This proper registration of the holes 9 with a corresponding number 75 of the holes 7 through both members 1 and 2 is

assured by the proper placement of the member 3 upon the member 2 by means of the pins 12 which require such registration of said holes; and said pins 12 also require the holes 9 to register with the holes 7 formed through the member 1 when said member 1 is placed upon the member 3 in connection with the pins 12.

5 After the cement has sufficiently dried, the vamp structure is removed from the template and is ready for use in making a shoe.

10 By this invention I am enabled to use a relatively soft and pliable member 2 and to obtain the desired stiffening of the toe portion of the vamp structure and of the shoe by the box toe member 3 and to provide registering perforations 15 which may function both as ornamentations and as ventilating means.

Vamp structures of this kind may be made with facility and inexpensively and provide a structure that is pleasing in appearance and that may 20 be worn with comfort.

The arrangement and the procedure may be varied within the scope of equivalent limits without departure from the nature and principle of the invention.

25 I claim:—

1. The method of making a shoe vamp structure including the steps of adhesively uniting inner and outer members, forming perforations through said members while they are adhesively 30 united, separating the foreparts of said inner and outer members, placing between the forepart of said inner and outer members a box toe member having therethrough perforations larger than said first named perforations in position in which 35 said perforations through said box toe member register with the perforations through said inner and outer members, and then adhesively uniting said box toe member with said inner and outer members in position in which the perforations 40 through said three members are in registration.

2. The method of making a shoe vamp structure including the steps of attaching together the rear portions of inner and outer members, forming perforations through the foreparts of said 45 inner and outer members while said members are attached together, separating the foreparts of said inner and outer members, placing between said members a box toe member having perforations therethrough larger than said first named 50 perforations in a position in which said perforations through said box toe member register with said perforations through said inner and outer members, and then attaching together the foreparts of said inner and outer members and said 55 box toe member.

3. The method of making a shoe vamp structure including the steps of attaching together inner and outer members, forming perforations through said inner and outer members while they 60 are attached together, separating the foreparts of said inner and outer members, forming perforations through a box toe member of larger size than said perforations through the foreparts of said inner and outer members, mechanically holding said box toe member upon one of said first named members in a location in which said perforations through said box toe member register with said perforations through that one of 65 said first named members upon which said box toe member is placed, and then mechanically locating the other one of said first named members upon said box toe member in a position in which said perforations through said other member 70

register with said perforations through said box toe member.

4. The method of making a shoe vamp structure including the steps of attaching together 5 inner and outer members, forming perforations through said inner and outer members while they are attached together, separating the foreparts of said inner and outer members, forming perforations through a box toe member of larger 10 size than said perforations through the foreparts of said inner and outer members, mechanically holding said box toe member upon one of said first named members in a location in which said perforations through said box toe member register 15 with said perforations through that one of said first named members upon which said box toe member is placed, then mechanically locating the other one of said first named members upon said box toe member in a position in which said 20 perforations through said other member registers with said perforations through said box toe member, and then applying pressure to said members and adhesively uniting them.

5. The method of making a shoe vamp structure including the steps of providing an assembly 25 of inner and outer members having a mass of openings therethrough, separating the foreparts of said inner and outer members, forming a mass of perforations through a box toe member in an 30 arrangement corresponding to the arrangement of openings in one of said first named members, mechanically holding said box toe member upon that one of said first named members in a location in which said perforations through said box 35 toe member register with said openings through that one of said first named members, and then locating the other of said first named members upon said box toe member in a position in which openings through said other member register 40 with perforations through said box toe member.

6. The method of making a shoe vamp structure including the steps of providing an assembly 45 of inner and outer members having a mass of openings therethrough, separating the foreparts of said inner and outer members, forming a mass of perforations through a box toe member in an arrangement corresponding to the arrangement 50 of openings in one of said first named members, mechanically holding said box toe member upon that one of said first named members in a location in which said perforations through said box toe members register with said 55 openings through that one of said first named members, and while thus mechanically held; bringing the other member of said assembly of first named members into contact with the box toe member, and adhesively uniting all of said members together.

7. In the art of making shoes, the process comprising, providing a vamp and lining having 60 therein a mass of ventilating openings, providing a separate box toe member having therein a mass of ventilating openings, passing mechanical members through the openings in the box toe member and one of said other members, and while the mechanical members remain in the 65 openings in said box toe member and one of said other members; adhesively uniting said vamp, lining and box toe member all together.

8. In the art of making shoes, the process comprising, assembling and connecting together an

exterior upper section and its lining, simultaneously perforating a mass of apertures through said assembled exterior upper section and lining, separately perforating a stiffening member with a mass of apertures arranged in corresponding 5 relation to the apertures in the first named parts, separating the exterior upper section and its lining sufficiently to permit interposition of the stiffening member, interposing the stiffening member between said exterior upper section and 10 its lining, and connecting the stiffener to the other layers in such relation that the apertures will be aligned with each other.

9. In the art of making shoes, the process comprising, perforating a vamp member with a mass 15 of apertures, separately perforating a box toe member with a correspondingly arranged mass of apertures larger in size than the apertures of the vamp member, passing mechanical members through a plurality of selected apertures in the 20 vamp member so that said mechanical members project through the vamp member, placing the box toe member upon the vamp member with the edges thereof in substantial alignment and with the mechanical members projecting through 25 apertures in said box toe member, and while in such position; adhesively uniting said box toe and vamp member, supplying another perforate vamp member, and adhesively uniting said other perforate vamp member to the box toe member. 30

10. The method of making a shoe vamp structure including the steps of perforating a mass 35 of apertures through a vamp member, separately perforating a mass of correspondingly arranged apertures through a box toe member, the apertures in the box toe member being larger than the apertures in the vamp member, adhesively uniting said perforated box toe member to said perforated vamp member in position such that the perforations therein register with each other, 40 supplying another perforate vamp member, and adhesively uniting said other perforate vamp member to said box toe member so as to enclose the box toe member between the vamp members.

11. A method of making a shoe structure including a plurality of superposed parts, comprising uniting two parts, perforating said united parts simultaneously, perforating a third part 45 similarly to the united parts, aligning the perforations of the several parts by disposing corresponding perforations about the upstanding pins of a template, and uniting said third part with said united two parts in aligned relation. 50

12. A method of making a shoe structure including a plurality of superposed parts, comprising permanently uniting two parts, perforating said parts simultaneously, perforating a third part 55 with larger similarly disposed perforations, aligning the perforations of the several parts by disposing corresponding perforations about the upstanding pins of a template, and uniting said several parts in aligned relation. 60

13. A method of making a shoe structure comprising perforating two superposed united parts according to a pattern, perforating a third part 65 according to the same pattern, mechanically holding said united parts and said third part in superposed relation so that corresponding perforations are aligned, and uniting said parts in this aligned relation.
